(57) **CLAIM**

The ornamental design for a welding clamp having two magnets with removal tabs and a hinge, as shown.

DESCRIPTION

FIG. 1 is a bottom, rear, left side, perspective view of a welding clamp having two magnets with removal tabs and a hinge showing my new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a top, right side, perspective view thereof;

FIG. 9 is a bottom, right side, perspective view thereof;

FIG. 10 is a bottom, right side, perspective view thereof with the hinge rotated inward; and,

FIG. 11 is a bottom, right side, perspective view thereof with the hinge rotated outward.
